APPARATUS FOR CONTROL OF ROOF LOCATION IN THE FORMATION OF UNDERGROUND CAV- ERN BY SOLUTION MINING

Carl T. Brandt, Bartlesville, Okla., assignor to Phillips
Petroleum Company, a corporation of Delaware

Application January 18, 1954, Serial No. 404,476

6 Claims. (Cl. 262—3)

This invention relates to an improvement in the means for mining a soluble material, such as rock salt, with a solvent. This invention relates to that class of mining in which a solvent, such as water, is introduced into a well drilled into a formation of salt and the resulting solution containing salt is discharged from the said well, and in which a non-solvent, such as air, is introduced into the well to form a protective layer between the solvent and the roof of the forming cavity. In one of its more specific aspects, this invention relates to an improved means for preparing an underground storage cavern in a soluble formation.

In recent years, a great deal of consideration has been given to the problem of storage of materials which, for economic reasons, are produced on a year-round basis, but which have heavy seasonal consumption rates. That is, large volume storage facilities are required. This problem is being solved, in the case of liquids or easily liquefiable materials, by means of underground storage caverns formed in salt formation.

A method now in use, in forming underground storage caverns, for dissolving salts by means of wells drilled through the bed, requires the circulation of liquid solvent through casings either to the top or bottom of the opening. If the liquid is introduced at the top of the bed, it floats on the heavier salt laden solution and continues to attack the salt near the top of the opening. As this fresh solvent dissolves salt, it sinks and is replaced so that fresh solvent is always near the surface. Even when the solvent is introduced near the bottom of the bed, it will rise through the heavy salt laden solution to the top of the opening. In either case, the chief point of attack on the salt is near the surface of the solvent.

The undesirable tendency of the chamber to come with resultant over development of the roof can be minimized if the distance between the top and bottom of the chamber in which dissolving is taking place is held to a minimum. When this distance is held to a minimum, the chamber tends to take the shape of the much more desirable frustum of a cone.

In order to control the height of the chamber in which dissolving is taking place, a non-solvent fluid, such as air, is introduced into the cavern. This fluid, having a density less than the solvent, floats on the solvent and protects the roof and upper side of the cavern from attack by the solvent. As a result, the roof height is held constant and all dissolving takes place below the top of the chamber.

When this portion of the cavern reaches the desired diameter, the non-solvent is removed thereby exposing the roof to dissolution. The dissolving of the roof can proceed until the desired thickness has been removed, at which time, the non-solvent is again introduced and roof dissolution stopped. Since the bottom has already been dissolved out, by controlling the thickness of the roof, we are actually holding the distance between the top and the bottom of the chamber to a minimum and forcing the chamber to take the shape of a frustum. By

2

repetition of this operation, we can form a frustum on top of frustum which will combine to form a cylindrical chamber with a horizontal flat top. If the horizontal flat top formed is located below the bottom of the outer casing previously described, then only a minimum of non-recoverable storage is created.

A serious disadvantage of the present systems is that the non-solvent is introduced under pressure and its total volume, where the non-solvent is a gas such as air, is dependent upon pressure and temperature relationships. To adjust the non-solvent level, it has been necessary to either regulate pressure or change the length of the protective casing which requires the use of heavy equipment at considerable expense. I have found that the solvent level, and consequently the protected depth, can be easily and readily maintained or changed, as desired, by the use of a small diameter vent pipe communicating from the desired solvent level to the earth's surface. The solvent level can be changed by simply raising or lowering the vent pipe or level control pipe.

An object of this invention is, therefore, to provide a means for regulating the solvent level in underground mining of a salt when injecting a solvent into a well drilled into the salt and flushing the resulting solution from the resulting cavity. A further object of my invention is to provide a means for controlling the cavity shape and roof location in preparing a cavern in a salt formation by means of a solvent. A still further object of my invention is to provide a means for preparing an underground storage cavern of the desired size and shape formed in a rock salt bed.

In discussing this invention, I will use as an illustration, the formation of an underground storage cavern in a bed of rock salt. I will use water as the solvent and air as the non-solvent. It will be seen by those skilled in the art that my invention is equally applicable to underground cavern forming in any soluble material deposited in underground beds. Water and air are the most abundant and cheapest materials available for the respective purpose of solvent and non-solvent, however, other materials can be used, if desired.

It has been the general practice in the formation of underground caverns in salt formation by dissolving to first drill a well from the surface to a position in the formation approximating the desired location in the top of the cavern. A permanent casing between the surface and the salt formation is then set and cemented in place, the cement making a tight seal. The hole is then drilled through the permanent casing down to a position approximating the desired location of the bottom of the cavern. A protective string is then placed inside the permanent casing and lowered to well below the seat of the permanent casing. A wash string is then placed inside the protective string and projects below the protective string to a position closely spaced to the bottom of the well. In normal operation, water is put into the well through the wash string, and brine is removed through the annular space between the wash and protective strings, however, the wash direction can be reversed.

Theoretically, one of the functions of the protective string is to protect the permanent casing seat. However, due to factors previously discussed, this has not been true, the fresh solvents on top dissolving the salt seat away.

According to my invention, a compressor is tied into the annular space between the permanent casing and the protective string and into the fresh water supply line (wash string). An open end small diameter pipe is inserted through the annular space between the permanent string and the protective string and is lowered to the desired water level and the upper end is open to the atmosphere. The bottom of the open end pipe, of

course, must be above the brine outlet string. This small open end pipe is called the "level control pipe."

The fresh water line is opened and the well is filled. With the well full of water, the compressor is started. As pressure builds up, the level of the water will be forced downward and the displaced water will move out through the brine discharge line. The water will continue to be forced downward until the bottom of the level control pipe is open to air and the excess air is released to the atmosphere. As the pressure is thus released, the water will again rise, closing off the level control pipe and the cycle is repeated.

I have found that very close control of the liquid level in underground mining can be maintained by the use of my apparatus. When the liquid level is forced down below the bottom of the level control pipe, the air escaping acts as an air lift and pushes brine ahead of it as it escapes. For that reason, it is desirable to use a small diameter pipe so as to keep the volume of brine low and to use a small volume of air, thereby minimizing the amount of blow off. For these reasons, I prefer as my level control pipe a conduit of less than one inch (1") diameter and have found that a standard $\frac{1}{2}$ " diameter pipe gives excellent results. I have also found that an air rate from $\frac{1}{4}$ to 1 cubic foot per minute (standard conditions) is sufficient even in relatively large diameter caverns, say up to 50 feet. In general, these caverns will not be so large since diameters greater than 20-35 feet may cave in from the roof. Of course, the maximum diameter will depend upon the particular formation and the factors determining this are outside the scope of this invention. However, once this has been determined, my invention is useful in controlling the diameter in the desired range.

I will further describe my invention by referring to the attached drawing which is a diagrammatic vertical section showing my invention in a typical cavern forming operation.

I will describe a typical installation used for preparing an underground cavern in a rock salt bed for underground storage. I will use water as my solvent and air as my non-solvent, since these materials are usually readily available in large quantities and at low cost. The dimensions used are typical but are not limiting.

Referring to the drawing, a well 1 is drilled from the earth's surface 2 into the salt 3 to a position near the desired cavern bottom. A 13 $\frac{3}{8}$ " O. D. permanent casing 4 extends from the earth's surface to shoulder 5 within the rock salt bed. This casing is sealed fluid tight by cement 6. This casing will remain in place after the cavern is formed and will serve as an access conduit for the underground storage equipment to be later installed. This permanent casing is capped by flange 6a. An 8 $\frac{3}{8}$ " O. D. protective string 7 passes through flange 6a and is centrally located within the protective casing and projects into the well, generally below the highest desired liquid level. This protective string is sealed to flange 6a and is in turn capped by flange 8. A 4 $\frac{1}{2}$ " O. D. wash string 9 passes through and is sealed to flange 8. This wash string is centrally located in the protective string and projects below the protective string to a position approximating the desired level of the cavern floor. A fresh water conduit 10 is tied into the protective string. The wash string is connected to a brine conduit 11 which leads to a brine pit, not shown.

A standard $\frac{1}{2}$ " pipe 12 passes through flange 6a and is located in the annular space between the protective string and the permanent casing. This $\frac{1}{2}$ " level control pipe projects downward to a position equal to the desired liquid level within the well. The upper end of this pipe is open to the atmosphere. This level control pipe is sealed, generally by means of packing gland, to the flange 6a. A compressor 13, is connected to the permanent

ent casing by means of 1" conduit 14. A $\frac{1}{2}$ " conduit 15 connects conduit 14 with protective string 7.

In the operation of this embodiment, fresh water flows through the fresh water conduit 10 to the protective string 7 and into the well 1. This water dissolves salt 3 and the more concentrated solution settles to the bottom of the well and is forced out through the tubing (9). The compressor 13 is started and air flows through conduit 14 to annular space between the permanent casting 4 and the protective string 7. Air also flows through conduits 14 and 15 to the protective string 7 where it mixes with fresh water. The pressure will build up in the cavern, forcing brine up through wash string 9 and conduit 11 to the brine pit. As has been hereinbefore indicated, the air pressure will continue to build up, forcing the liquid level down to the bottom of the liquid level control pipe when the air will escape, releasing the pressure. The reduction in pressure will allow the liquid to rise and close off the bottom of the pipe. This in turn will cause a buildup of pressure and another lowering of the water level repeated and thereby maintain the liquid level.

As has been hereinbefore said, the fresh solvent will tend to stay in the upper part of the liquid phase and being less concentrated will dissolve the salt at a more rapid rate than will the more concentrated solution in the lower strata. As a consequence, the well will take on the appearance of a frustum of a cone. When the base of the cone (upper level) reaches the desired diameter, the packing gland sealing the liquid level control pipe is loosened and the pipe is raised after which the gland is tightened and the pipe is again sealed. Then the procedure for admitting air and water as described above is repeated. This procedure is continued until the entire cavity is formed.

Air admitted to the fresh water is partially dissolved therein and is carried by this fresh water to all portions of the cavern. As this water dissolves salt, the air is released and will displace water in spaces such as space 40 16 behind bridges such as bridge 17.

I have described my invention in one of its preferred embodiments. Those skilled in the art will see many modifications which can be made without departing from the scope of this invention. I have described my invention wherein an underground storage cavern is prepared in a rock salt bed. My invention is equally applicable for forming caverns in other soluble deposits. Other solvents may be employed, for example, hydrocarbon, ammonia or alcohol, depending upon the particular soluble material. Non-solvents other than air can be employed, for example, waste gases can be used as non-solvents for rock salt. The liquid level control pipe shown as being open to the atmosphere. If it is undesirable to exhaust the non-solvent to the atmosphere, this pipe can be connected to a collection vessel. If it is undesirable to spray the brine of other solvents to the atmosphere, a liquid trap can be placed in the liquid level control pipe and the liquid removed can be conducted to the brine pit.

I claim:

1. An apparatus for underground mining of a soluble material by means of a liquid solvent said apparatus comprising in combination means for introducing solvent into an underground bed of said soluble material, means for withdrawing solvent having soluble material dissolved therein from said bed, means for introducing a non-solvent lighter than said solvent and non-miscible therewith to top of said solvent introduced to said bed, and an open conduit communicating from the desired solvent level in said bed to the atmosphere above the surface of the earth, said conduit being adjustable vertically.

2. An apparatus for controlling the cavern shape and roof location in underground mining of a soluble material by means of a liquid solvent said apparatus com-

prising in combination means for introducing solvent into an underground bed of said soluble material, means for withdrawing solvent having soluble material dissolved therein from said bed, means for introducing a non-solvent gas into the cavity formed in said bed by said solvent and a vertically adjustable conduit of relatively small diameter adjustably disposed so as to communicate between the desired liquid solvent level and the atmosphere above the earth's surface.

3. The apparatus of claim 2 wherein the inside diameter of the vertically adjustable conduit is less than one inch.

4. The apparatus of claim 3, wherein the diameter of the adjustable conduit is within the range of one-quarter (1/4) to one (1) inch.

5. An apparatus for underground mining of a salt deposited in underground beds by passing a solvent into and out of the said salt bed, thereby dissolving the salt and wherein a non-solvent of lesser density than the solvent is continuously passed into the cavity resulting from dissolving the salt, the apparatus comprising in combination a permanent casing extending from the salt bed to the earth's surface and being cemented fluid tight into place, the permanent casing having a fluid tight cap at its upper end; a protective string of smaller diameter than the permanent casing passing through the permanent casing cap and projecting below the bottom of the permanent casing into the salt bed, the protective string being so disposed as to have a common vertical axis with the permanent casing and thereby providing for an annular space between the protective string and the permanent casing; a fluid tight cap affixed to the upper end of the said protective string; a wash string of lesser diameter

than the protective string passing through the cap of the protective string and projecting below the bottom of the protective string into the salt bed to a position approximating the desired level of the cavity floor, the said wash string having a common vertical axis with the protective string and thereby providing for an annular space between the wash string and the protective string; means for admitting fresh solvent to the annular space between the wash string and the protective string; conduit means for removing solution from the upper end of the wash string; a vertically adjustable conduit having an inside diameter of less than one inch communicating from the desired solvent level to the atmosphere; the said adjustable conduit passing through the permanent casing cap and the annular space between the permanent casing and the protective string; pumping means for a non-solvent; a conduit means connecting the outlet of the said pumping means and the annular space between the permanent casing and the protective string; and conduit means connecting the last said conduit means and the annular space between said protective string and said wash string.

6. The apparatus of claim 5, wherein the salt is rock salt, the solvent is water, the non-solvent is air, and the adjustable conduit has a diameter in the range of one-quarter (1/4) to one (1) inch.
